UNITED STATES PATENT OFFICE

GEORGE R. TREPTOW, OF CHICAGO, ILLINOIS, ASSIGNOR TO CAMEL COMPANY, OF CHICAGO, ILLINOIS, A CORPORATION OF ILLINOIS

TRACK MEANS

Application filed November 21, 1929. Serial No. 408,722.

This invention relates to car doors for railway house cars and more particularly it relates to a track means for supporting said doors for sliding movement.

5 At the present time it is the almost universal practice in steel car and steel door construction to utilize brackets, known as track brackets, connected to the side sill of a steel car, which brackets carry and support the track for sliding steel doors used on such cars. This construction necessitates the use of a large number of castings, usually of malleable iron, which castings are of uncertain quality and are subject to shrinking, cracking and are expensive. Further, in riveting these brackets to the side sills of a car a total of six (6) rivets for each bracket is often required, involving consequently a great deal of labor and added expense.

10 This invention has, for an object, to obviate the expense and labor incident to the use of track brackets for supporting a track.

It is also an object of this invention to introduce a very desirable economy in car door construction by the elimination of the use of track brackets.

15 It is a further object to reduce the number of parts heretofore employed in steel door construction by dispensing with the track brackets and by securing the track or tracks directly to a part of the steel car.

20 This invention has, for an object, the drainage of water and proper disposal of other foreign matter which may fall upon the track.

25 Other objects and advantages of the invention will become apparent from the description of the invention and from the accompanying drawing forming part thereof, in which

30 Figure 1 is a fragmentary elevation of an all steel car and steel door construction with the subject matter of the invention applied thereto.

35 Figure 2 is a section on a plane indicated by the line 2-2 of Figure 3.

40 Figure 3 is a section on a plane indicated by the line 3-3 of Figure 1.

45 Figures 4 and 5 are elevation and sectional

views, respectively, of a modified track structure.

Referring first to the construction shown in Figures 1 to 3, inclusive, of the drawing, the numeral 10 designates an all steel or metal door, shown in the present embodiment as a bottom supported door. Secured by means of rivets 12 adjacent the lower corners of the door are hangers 11. A roller 13 is carried by each of these hangers and is 55 rotatably mounted therein by means of a pin 14. Projecting downwardly from each of the hangers on the outside of the track 16 are extensions 15 which limit the inward movement of the door toward the car. 60 Opening movement of the door is limited by stops 25. The track 16, upon which the door slides, is positioned below the floor 24 of the car and is clearly shown in Figure 3 of the drawing, connected directly to the side sill 22 without the intervention of track brackets. 65 The track may be, and preferably is, formed of rolled steel. The track is provided with a downwardly extending flange 17, through which rivets 23 extend in fastening the track directly to the side sill. 70 Extending horizontally and forming preferably, though not necessarily, an integral portion of the track is the flange 18 adapted to support the rollers 13 which are carried by the door hangers. Connecting the attaching flange 17 with the roller supporting portion 18 are two angularly related flanges or portions 19 and 20. These angularly related flanges are so positioned that they present a reentrant angle directed inwardly toward the car for the purpose of permitting drainage of water which may drip from the door onto the track, or which may be blown onto the track. 75 It is evident that other foreign substances will also be shed from the track due to the arrangement of the angularly connecting flanges.

To further aid in the proper drainage and disposal of foreign subject matter from the track, filler or spacing plates 21 are employed. These filler plates are interposed between the attaching flange 17 and the side sill 22, which filler plates are positioned at 80 predetermined spaced points longitudinally 85

of the car for a purpose hereinafter referred to. By the use of these filler or spacing plates the track is spaced from the side sill, consequently providing openings between the track, the side sill and adjacent filler or spacing plates, permitting disposal of water and other foreign substances from the track.

To maintain the desired relation between the track, the filler plates and the side sill, the rivets 23 are extended through the members mentioned, there being preferably two rivets used with each filler plate. The filler plates are so spaced relative to each other that the ordinary spacing used where track supporting brackets are employed, is maintained. Because of this fact, it is apparent that no additional labor or fabricating of holes in the side sill is required.

Referring to the modification shown in Figures 4 and 5 of the drawing, the track is designated by the reference numeral 26. The track is preferably formed with an integral attaching flange 27, similar to the flange 17 of the track 16 and with a roller supporting flange 28. Connecting these flanges are the angularly related portions 29 and 30. This construction is quite similar to that illustrated in Figure 3 of the drawing. It is noted, however, that the flange 29 shown in Figure 5 of the drawing is inclined downwardly relative to the flange 30 for the purpose of aiding in the disposition of water and other foreign substances.

It is apparent from the foregoing description that the track constituting the subject matter of this invention obviates the use of track brackets and results in a consequent economy and saving. No sacrifice in the strength of the track is necessary, while proper drainage of water and proper disposal of other matter is permitted.

It is known to be old in the car door art to connect the track directly to a wooden house car which is provided with a wooden door and no claim is consequently made to such construction. However, no art is known to the applicant which discloses a track connected directly to a car where both the car and the doors therefor are of all steel construction.

This novel construction is shown and described by what is now considered the preferred embodiment in the accompanying drawing and specification. It is to be understood, however, that the invention is not limited to such construction which is merely illustrative, but contemplates all changes and modifications coming within the scope of the claim appended hereto.

I claim:

The combination with a continuous side sill of a metallic railway car provided with a door opening and a metallic door to close said opening, of a track for supporting said door for sliding movement, said track being

secured directly to said sill and having a vertical securing flange, a horizontal flange extending outwardly from said securing flange, said horizontal flange lying below the floor of said car and the lower edge of said door, a vertical flange extending upwardly from said horizontal flange, the track terminating outwardly of said car in a horizontal tread, said horizontal flange and said last mentioned vertical flange presenting an angle directed toward said sill and lying below the floor of the car, said lower edge of said door being positioned between said last mentioned vertical flange and the sill of said car.

Signed at Chicago, Illinois, this 14th day of November, 1929.

GEORGE R. TREPTOW.
